DESIGN FOR A MUFF

Edward A. Schnur, New York, N. Y.

Application July 2, 1940, Serial No. 93,390

Term of patent 14 years

To all whom it may concern:

Be it known that I, Edward A. Schnur, a citizen of the United States and a resident of the Borough of Manhattan, county of New York, State of New York, have invented a new, original, and ornamental Design for a Muff, of which the following is a specification, reference being had to the accompanying drawing, forming a part thereof, wherein,

Fig. 1 is a side perspective view of a muff showing my new design;

Fig. 2 is one end elevational view thereof; and
Fig. 3 is the other end elevational view thereof.

I claim:

The ornamental design for a muff, substantially as shown.

EDWARD A. SCHNUR.
